UNITED STATES PATENT OFFICE.

WILLIAM W. DICKINSON, JR., OF LITTLE ROCK, ARKANSAS.

APPARATUS FOR BURNING BRICKS.

1,403,301.

Specification of Letters Patent. Patented Jan. 10, 1922.

Application filed March 3, 1921. Serial No. 449,310.

To all whom it may concern:

Be it known that I, WILLIAM W. DICKINSON, Jr., a citizen of the United States, residing at Little Rock, in the county of Pulaski and State of Arkansas, have invented a certain new and useful Improvement in Apparatus for Burning Bricks of which the following is a full, clear, and exact description, reference being had to the accompanying drawings.

This invention relates to the burning of bricks and has special reference to the means for producing heat whereby the burning is effected. The objects of the invention are the provision of brick burning apparatus whereby the requisite heat can be produced by the combustion of coal and this with a minimum of manual labor and by the use of simple and comparatively inexpensive equipment; the provision of portable coal burning equipment for use outside of but in conjunction with brick kilns which shall operate with a minimum of the heat loss with a minimum of permanent construction; the operation of coal burning means for brick kilns which shall obviate the necessity of inserting fuel inside the kilns or the withdrawal of ash from the kilns and which shall not interfere with the employment of the gas, oil, or other alternative heating agents if desired; the provision of a portable kiln furnace with portable kiln walls; while further objects and advantages of the invention will become apparent as the description proceeds.

In the drawing accompanying and forming part of this application I have illustrated one embodiment of my said invention although it will be understood that I do not thereby limit myself to any of the particular constructions therein shown which can be varied very widely within the scope of my inventive idea. In these drawings Fig. 1 is a perspective view showing my improvements as applied to a continuous row of kilns; Fig. 2 is a vertical sectional view through the fire box and one of the arches of the kiln, and Fig. 3 is a top plan view of said kiln together with the coal burning means.

Describing by reference characters the parts shown in these drawings 1—1 represent brick kilns and 2—2 the arches or eyes which traverse the lower part of the same. These arches ordinarily serve as fire boxes for the combustion of wood, coal, or gas, and

also as distributing channels whereby the products of such combustion are led to all parts of the structure through the loosely piled brick. In the present embodiment I have illustrated these kilns as arranged in a row, the eyes or arches extending transversely of such row, and the space between the adjacent kilns being occupied by down-draft passage-ways 3—3 as described in my former Patent No. 1,355,821, dated October 19, 1920. The end of said passage communicates with the upper part of the kiln at one side and is formed at its lower end with an outlet arch which communicates with the inlet of a portable conduit 4 whose side is provided with a plurality of connections 5 which lead to the arches of the next succeeding kiln. In this way the partially cooled gas escaping from the first kiln is employed to preheat the second kiln, and in turn to dry other succeeding kilns until its dew point is reached, whereupon it is received in down-turned elbows 6—6 which communicate with an under-ground or other passage-way (not shown) leading to an exhaust fan or other draft producing appliance. It will be understood that my invention is not restricted to use with this kind of kiln although it offers particular advantages in such combination. It is only necessary for its economical performance that the kilns should be arranged in a row with their arches transverse of such row and a railroad track 7 or equivalent roadway provided at each side thereof.

Upon each of these tracks or roadways and opposite each arch I locate an automatic stoker 10 of any suitable type. I prefer to employ one such stoker for each arch and to combine a sufficient number of the same upon a single car 11 to correspond with all the arches of a single kiln, although a smaller number per car could be employed. Indeed the cars can be made very short and only one stoker employed per car. I have here shown for illustrative purposes a kiln with five arches and cars with five stokers, but the kilns can be made either longer or shorter as also may the cars. The top of each car is provided with a hopper 12 for the reception of fuel, which is distributed and apportioned by the auger-conveyer 13 to channels 14 leading to the different grates 14^a. All the grates are operated by chains 15 from a shaft 16 suitably geared to a driving motor 17. The interior of the car

body is provided with combustion chambers 18, one for each grate, the whole forming a portable furnace; and the side of the car next the kiln is formed with openings 5 19, one opposite each arch and connected thereto by a movable thimble 20 of heat resistant metal which may either be a high-temperature metallic alloy or a refractory ceramic.

10 These cars 11 are preferably used in pairs, one being at each side of the kiln, and the tracks upon which they run are of very great additional utility, since a coal car 22 can be run in on the one track and 15 an empty car 23 on the other track, the former to supply the fuel and the latter to receive the bricks from the kiln which have been sufficiently cooled to handle. 25—25 represents a travelling crane movable on 20 tracks 26—26 located above the row of kilns and used for transferring coal from the car 22 to the hoppers 12 by the aid of a clamshell bucket 27, and also for the manipulation of brick handling devices to build the 25 new kilns and demolish the burned kilns. The crane is preferably movable to a point completely above the car tracks wherefore the track 26 preferably has one rail outside each railroad track.

30 I have here shown the sides of the kilns as encased in a scoving made in large portable panels 30—30 as described and claimed in my application Serial No. 429,610 filed December 10, 1920. This, while not imperative, is of great practical convenience and provides a kiln wherein both the walls and the furnace are portable, thereby enabling the construction and demolition of the kiln-body entirely by mechanical means and 35 without obstruction of any kind. As a result of my improvement the kilns are built, scored, coaled, fired, and demolished mechanically, with a minimum of hand labor and a maximum of speed. I prefer and rec- 40ommend that each stoker be of the size and capacity known as "50 horse power," that is, of a grate-area sufficient to consume the amount of coal required per hour to operate a fifty horse power boiler.

45 It will be understood that great changes may be made in detail within the scope of my invention and that I do not limit myself in any way except as specifically recited in the annexed claims.

50 Having thus described my invention what I claim is:

1. The combination with a row of brick kilns, of an automatic coal stoking device movably supported at each side of the row 60 and adapted to be presented to said kilns successively in heating relation.

2. The combination with a row of brick

kilns and a fixed track therealong, of a portable, coal-burning grate outside of and independent from said kilns, and means for 65 movably supporting said grate whereby it may be transported along said track from kiln to kiln and presented thereto in heat supplying relation.

3. The combination with a row of brick 70 kilns, each having arches transverse to the length of the row, of automatic coal stoking devices movably supported one at each side of said row and adapted to be used in pairs, each device having a number of 75 combustion chambers equal to the number of arches in a kiln and connected one chamber to each arch.

4. The combination with a brick kiln having arches, of a movable furnace located 80 outside of but adjacent to said kiln, said furnace having a grate for each arch, and means enclosing each grate and communicating with the respective arch for conveying the products of combustion thereto. 85

5. The combination, with a brick kiln having arches, of a movable furnace located at the side of said kiln and having openings 90 in line with said arches, movable thimbles of refractory material establishing communication between said openings and arches, and coal-burning grates in said furnace. 95

6. The combination, with a brick kiln having arches, of a movable furnace located at the side of said kiln and having openings in line with said arches, movable thimbles of refractory material establishing communication between said openings and arches, and automatic stoking mechanism for said 100 furnace.

7. The combination with a row of brick kilns, having transverse arches, of a railroad track at each side thereof, a movable furnace supported on each of said tracks 105 and adapted to deliver its combustion products directly into said arches, each furnace comprising a supply hopper and automatic stoking mechanism, a third track and mechanism carried thereby for conveying coal 110 to said hoppers.

8. In brick burning apparatus, in combination, a row of kilns having transverse arches, a railroad track at each side thereof, a crane track above having one rail outside each railroad track, portable furnaces on said tracks and detachably connected to the arches of a kiln, and a traveling crane on said track adapted both to transport coal to said furnaces and to construct and demolish said kilns. 115

In testimony whereof, I hereunto affix my signature.

WILLIAM W. DICKINSON, JR.
